UNITED STATES PATENT OFFICE.

FRANK C. ROBERTS, OF PHILADELPHIA, PENNSYLVANIA

FURNACE-CHARGING APPARATUS.

No. 910,233.

Specification of Letters Patent.

Patented Jan. 19, 1909.

Application filed December 23, 1907. Serial No. 407,816.

To all whom it may concern:

Be it known that I, FRANK C. ROBERTS, residing at Philadelphia, in the county of Philadelphia and State of Pennsylvania, have invented new and useful Improvements 5 in Furnace-Charging Apparatus, of which the following is a specification.

The object of the improvement is to secure a more uniform distribution of the materials charged into the furnace. It is found, under 10 certain conditions as to the physical characteristics of the materials to be delivered into the furnace, that in the case of furnace charging apparatus commonly in use, the fine material is apt to separate from the coarser materials and lie in a certain portion 15 of the hopper. This condition naturally leads to the finer materials being delivered to one portion of the furnace, making it more difficult for the blast supplied the furnace to 20 penetrate the materials uniformly throughout the cross section of the furnace. The location of the finer materials in the hopper of the ordinary arrangement of charging apparatus, is practically identical each time 25 the materials are delivered into the hopper and the object I have in view—namely, the more uniform distribution of the materials within the furnace—will be secured if provision is made to revolve the hopper before 30 discharging the contents into the furnace.

I am aware that types of furnace charging apparatus are in use in which a revolving supplementary hopper is employed, said supplementary hopper located above, and discharging into the main hopper, the latter being stationary. In my improvement however, I revolve the main hopper, the supplementary hopper, if provided, being stationary. 40

The manner in which I attain my object will be clearly understood by reference to the drawings, which accompany this specification and in which—

Figure 1 represents an end vertical elevation, partly in vertical section, showing one embodiment of my invention; Fig. 2 is a vertical side elevation of the arrangement shown in Fig. 1, and Fig. 3 is a plan of said arrangement. Fig. 4 shows a second form of apparatus, and Figs. 5, 6, 7, 8, 8¹, and 9 show several details and modifications of construction.

Similar letters refer to similar parts throughout the several views.

Referring to Figs. 1, 2 and 3, A designates the furnace hopper, a its inclosing walls and B the closure for closing its mouth. B is supported by the hollow frustum or cone C which is in turn supported by the hollow cylindrical casting D having at its upper end, a flange E resting on a ring F which is furnished with two trunnion pins G at opposite points of its circumference, to each of which is attached a chain H passing over and attached at the top to segments of arcs K attached to the end of levers I, which levers are also equipped at the opposite ends with segments of arcs K₁. The levers I are pivoted at J. Chains H₁ are attached at the top to K₁ and at the bottom to an equalizing bar L which is in turn attached to piston rod M leading and fastened to a piston operating within steam cylinder N. A cylinder O is attached to the bottom of D thus forming a pocket 75 within which passes the lower end of cylinder P. P₁ is the continuation of P and forms the conduit for carrying away, to the points of distribution, the gases generated in the furnace while Q is a relief valve and P₂ a cylinder shield to protect the pocket formed by D and O. R is a truck supported on wheels r₁ resting on girders r₂ and carrying the fulcrums J of the levers I. S is a shield covering the hopper A and supported from R by 80 bars S₁. T is a skip car or cars for hoisting materials to the top of the furnace and delivering them into the chute or hopper U leading through S and into A by means of an opening X. The latter opening is provided 85 with a closure X₁ consisting of a slide valve operated by a steam cylinder X₂ acting through its piston, the piston rod X₃ and the levers X₄ (see Fig. 6). The outer edge of the shield S is provided with a flange S₂ extending downwards into a pocket a₂ formed at the upper edge of the inclosing walls a of A. The hopper A is supported freely on an annular casting Y which in turn rests upon and is attached to the metal work V inclosing 90 the furnace. W is an annular casting attached to the flange on A and extending under the upper flange of Y (to prevent the vertical displacement of A) and projecting downwards into the pocket formed by the 95 cylinder W₁ attached to the lower flange of Y. Z is a motor operating to revolve A through shaft Z₁, pinion Z₂ and rack Z₃ attached to A. The flange on A which rests on Y is provided with a lip a₃ extending down- 100 105 110

wards and inside of the upper flange on Y the purpose of the construction being to prevent the lateral displacement of A.

The operation is as follows:—The material to be charged into the furnace is carried up by one of the skip cars T and dumped into the chute or hopper U from whence it passes through the opening X into A. The motor Z is then actuated and the hopper A revolves any desired number of degrees, being freely supported on the upper flange of Y; B, C, D and O revolving with A, the latter parts being supported by F which is stationary and upon which they revolve. This operation of charging and revolving is repeated until the hopper A is filled with material to the desired extent; it is to be noted that A need not be revolved after the last skip load of material has been delivered into it. As an illustration; assume that after each charge the hopper A is revolved 45 degrees which would require eight charges to fill A; the first seven charges would be revolved 45 degrees but A would not be revolved after the eighth charge. After the above described operation the closure B and connected parts C D O and F are lowered in an obvious manner by means of the steam cylinder N it being borne in mind that in the apparatus shown, the steam pressure in cylinder N raises the closure B etc., to the position shown in Fig. 1 while the removal of the steam pressure from the cylinder allows B etc. to drop, thus opening the mouth of the hopper A and allowing its contents to be delivered into the furnace. It is to be noted that the shield S does not revolve with A but remains stationary and that, the valve X₁ being closed and the pocket a₂ being filled with water or sand (thus forming with S₂ a seal), gas is not permitted to escape from the furnace when B is lowered. It is also to be noted that the pocket formed by D and O is filled with water and that P is stationary, the depth of the pocket and P being such that the lowering of B and attached parts to the desired point, leaves the lower end of P immersed in water, thus forming a water seal and preventing the escape of gas. An overflow pipe d₁ is provided to discharge surplus water into trough S₃ from whence it passes to waste.

It is evident that by the above operation any inequality in the distribution of coarse and fine materials which may arise in delivering the materials into A is redistributed around the circumference of the furnace and that thereby I secure fairly uniform distribution of coarse and fine materials throughout the cross section of the furnace.

The hopper A as heretofore stated, revolves on the upper surface of Y and the purpose of the pocket formed by W₁ and Y is to provide a seal to prevent the escape of gas over the upper surface of Y; this is se-

cured by filling the pocket with water, sand or other suitable material.

The explosions which at times take place within the furnace have a tendency to lift the hopper A; the flange W attached to A and projecting under the upper flange of Y prevents such a result.

In all forms of furnace charging apparatus it is desirable to provide convenient means for the removal of old and the placing of new parts. This is accomplished in the present instance in the following manner. D is disconnected from C and B and B and C supported in any convenient manner; P is also disconnected from P₁, and allowed to drop into the pocket formed by D and O. The levers I are then secured in their upper positions and the piston rod M of the steam cylinder disconnected from L. The flange S₂ is detached and raised and the chute U disconnected from S. These operations result in P, P₁ and all connected parts, in addition to S₁ being carried by truck R which may then be moved to one side as shown in dotted lines at the left of Fig. 2. Truck R is then moved over the center of the furnace and C, B and the lower portion of the hopper A lifted out of their normal positions by any approved means and moved to one side as indicated in dotted lines at the right of Fig. 2. New parts may then be inserted and the described operation reversed.

Fig. 4 represents a second form of my improvement in which as before A is the hopper, B the closure and S the shield. In this case however, the skip car T delivers the materials into chute 6 which discharges into a supplementary hopper 7 provided with a closure 8. The closure B is supported by a rod b provided at its upper end with flanges b₁ (see Fig. 5) within which and around b is provided a ring 11 with trunnions b₂. Links b₃ and pin b₄ connect the parts to lever 9 which is operated in the usual manner by steam cylinder 10; the construction being such that B and b can revolve without turning 11 and connected parts. The closure 8 is supported by the hollow rod 12 carried from lever 13 by links 14 and operated in the usual manner by steam cylinder 15. S is a shield covering the hopper A and supported on the upper flange of A. Z Z₁ Z₂ Z₃ as in Fig. 1 constitute the driving mechanism for revolving A. The hopper A is supported by and revolves on Y; the annular casting W prevents the vertical displacement of the hopper while the lip a₃ prevents the lateral displacement of the hopper A; a seal is provided by W, W₁ and Y; all as in Fig. 1.

Attention is called to the fact that while in Figs. 1, 2 and 3 a construction is shown wherein the shield S is supported by R and does not rest on A, the construction shown in Fig. 4 provides that S be supported on the hopper A.

The operation of the apparatus illustrated in Fig. 4 is as follows:—The material to be charged into the furnace is carried up by one of the skip cars T and dumped into chute 6 from whence it passes into the supplementary hopper 7. The closure 8 is then lowered and the material allowed to pass into A after which 8 is raised and the opening between 7 and A, closed. The hopper A and contents 10 is then revolved by motor Z to any desired number of degrees, the closure B, rod b and shield S revolving with A. After the desired revolution of A has been accomplished, the closure B is lowered by the obvious action 15 of the steam cylinder 10 and the contents of A discharged into the furnace. This operation of charging and revolving is repeated (except as noted in illustration below) the number of degrees of revolution being increased each revolution to any desired extent in order that the distribution of coarse and fine materials secured in A may be re-distributed around the circumference of the furnace. As an illustration:—Assume that 20 upon the first charge of materials being delivered into A, the hopper A is revolved 90 degrees; the second charge is revolved 180 degrees; the third charge 270 degrees, while the fourth charge is not revolved but delivered 25 into the furnace in the position in which it is delivered into A. It is then seen that one of the charges should be delivered into the furnace without the revolution of A whether it be the last or the first charge. It 30 is evident that by the above described operation any irregularity in the distribution of coarse and fine materials which may arise in delivering the materials into A is re-distributed around the circumference of the furnace 35 and that thereby, I secure a fairly uniform distribution of coarse and fine materials throughout the cross section of the furnace. Figs. 7, 8 and 8¹ show a second form of support for the hopper A wherein A is supported 40 on wheels 3 resting in casting 1 which is provided with a pocket 2 into which a vertical flange a_5 of hopper A projects; it is evident that by filling the pocket 2 with water or other suitable material a seal will be formed 45 to prevent the escape of gas from the interior of the furnace. In this case the vertical displacement of the hopper A is prevented by shafts 16 carrying wheels 3, the ends of which shafts project over a flange 17 on a_5 and thus 50 prevent A from being displaced vertically. In the construction shown in Figs. 7, 8 and 8¹ a flange a_4 is provided on 1, said a_4 being inside of a_5 thus preventing the lateral displacement 55 of the hopper A. 60 It is obvious that in the arrangement shown in Fig. 4 it would be possible to support the shield S independently of the hopper A; one method of doing this is illustrated in Fig. 9 wherein the shield S is shown as supported 65 by the supplementary hopper 7.

Having fully described my invention, what I claim and desire to cover by Letters Patent is—

1. In a furnace, a hopper, a closure for said hopper, means for operating said closure, a shield over said hopper and supported independently of said hopper, an opening in said shield for delivering materials into said hopper, a closure for said opening, means for operating said closure and means for revolving said hopper and its closure. 70
2. In a furnace, a hopper, a closure for said hopper, means for operating said closure, a shield over said hopper and supported independently of said hopper, an opening in said shield for delivering materials into said hopper, a closure for said opening, means for operating said closure, means for revolving said hopper and its closure and means for preventing the lateral and vertical displacement 85 of said hopper. 80
3. In a furnace, a hopper, a closure for said hopper, means for operating said closure, a shield over said hopper and supported independently of said hopper, an opening in said shield for delivering materials into said hopper, a closure for said opening, means for operating said closure, a supplemental hopper for delivering materials to said opening and means for revolving said hopper and its 95 closure. 90
4. In a furnace, a lower main hopper, a closure for said hopper, means for operating said closure, a shield over said hopper and supported independently of said hopper, an opening in said shield, an upper supplemental hopper, located in said opening, a closure for said supplemental hopper, means for operating said closure, and means for revolving said lower main hopper and its closure. 100 105
5. In a furnace, a lower main hopper, a closure for said hopper, means for operating said closure, a shield over said hopper and supported independently of said hopper, an opening in said shield for delivering materials into said hopper, a closure for said opening and means for operating said closure, a supplemental hopper for delivering materials to said opening, a second opening in said shield located centrally over said lower 110 main hopper, a conduit for gas extending upwards through said second opening and forming a part of the means for operating the closure of said lower main hopper, an annular pocket near the top of said conduit, a circular gas flue having its inclosing walls extending downward into said pocket, a seal formed by said pocket and said gas flue and means for revolving said lower main hopper, its closure and said conduit. 115 120 125
6. In a furnace charging apparatus, a lower main hopper, a closure for said hopper, means for operating said closure whereby the contents of said hopper may be discharged symmetrically around the interior of the 130

furnace by one operation of said closure, a shield over said hopper, an upper supplemental hopper located in an opening in said shield, a closure for said supplemental hopper, means for operating said supplemental hopper closure and means for revolving said lower main hopper and its closure.

7. In a furnace charging apparatus, a lower main hopper, a closure for said hopper, means for operating said closure whereby the contents of said hopper may be discharged

symmetrically around the interior of the furnace by one operation of said closure, an upper supplemental hopper, a closure for said supplemental hopper, means for operating said supplemental hopper closure and means for revolving said lower main hopper and its closure. 15
